UNITED STATES PATENT OFFICE.

ROBERT W. FARRINGTON, OF BUFFALO, NEW YORK.

ELECTRIC CONTACT DEVICE.

No. 799,896.

Specification of Letters Patent.

Patented Sept. 19, 1905.

Application filed September 23, 1904. Serial No. 225,603.

To all whom it may concern:

Be it known that I, ROBERT W. FARRINGTON, a citizen of the United States, residing at Buffalo, in the county of Erie and State of New York, have invented new and useful Improvements in Electric Contact Devices, of which the following is a specification.

This invention relates to an electric contact device which is more particularly designed for electric trolleys, but which may also be used in electric dynamos, motors, &c.

One form of contact device heretofore in use consisted of a trolley-wheel which rotates with its periphery in contact with a conductor-wire. This construction is objectionable, owing to the small amount of contact which takes place at any one time between these parts, permitting the passage of but a small amount of electricity, and therefore limiting the efficiency of the devices which are supplied with the current. It has been proposed to overcome this objection by constructing the trolley in the form of a shoe or block which slidingly engages with the conducting-wire lengthwise over a considerable extent, which construction is also undesirable on account of the excessive friction and wear inseparable from such an organization.

The object of this invention is to produce an electric contact device for this purpose which furnishes ample contact-surface and which practically eliminates all friction, thereby obtaining the desirable features of both the wheel and shoe contact devices, but avoiding the undesirable features of the same.

In the accompanying drawings, Figure 1 is a sectional side elevation of a trolley-wheel embodying my invention. Fig. 2 is a fragmentary top plan view of the same. Figs. 3 and 4 are cross-sections of the same in lines 3 3 and 4 4, Fig. 1.

Similar letters of reference indicate corresponding parts throughout the several views.

The body of the electric contact device shown in the drawings is preferably constructed in the form of a rotary support or wheel, which consists, essentially, of a hub A, a rim B, connected by arms b or otherwise with the hub, and two annular flanges D D', arranged on opposite sides of the rim and forming an annular channel C between the same. One of the flanges is preferably formed integrally with the rim, arms, and hub, while the other flange is made separate and detachably con-

nected with the rim by any suitable fastening, the means for this purpose shown in the drawings consisting of screws c.

F represents a plurality of bearing-shoes whereby electrical connection is established between the trolley-wheel and the trolley-wire f or other electrical conductor. These shoes are arranged in an annular series or row in the channel which is formed around the periphery of the rim, each shoe having a contact or bearing surface e on its outer side, which is straight lengthwise of the shoe and concave transversely, as shown in Figs. 1 and 3. Each of the bearing-shoes is pivotally mounted on the wheel or support, so that the same can tilt or adjust itself on the wheel and permit its bearing-surface to engage its entire length at one time against the conductor-wire. For this purpose pivot-pins G are provided, each of which extends transversely through an opening g in the central part of one of the shoes and through coinciding openings g' g' in the adjacent parts of the flanges. The pivot-pins are preferably fixed in the shoes by a driving fit, brazing, or otherwise, while their ends are journaled in the openings g' of the flanges. When the shoes need to be removed from the support for repairs or replaced by new ones when worn out, this can be easily and readily done by simply removing the detachable flange D' from the rim of the support.

For the purpose of causing the shoes to normally assume a position in which they are practically parallel with the conductor-wire at the time of engaging the same means are provided which constantly tend to turn or tilt the shoes forwardly or in the direction which the support turns, so that the bearing-faces of the shoes are arranged obliquely to the periphery, or, in other words, tangentially to the axis of the support. This is preferably effected by making the rear or trailing ends of the shoes somewhat heavier than the front or advancing ends thereof. By this construction of the shoes the centrifugal force causes the rear ends of the shoes to be thrown outwardly during the forward rotation of the trolley-wheel, while the front ends thereof are swung inwardly and assume the position shown in Fig. 1.

As a substitute for the unbalanced construction of the bearing-shoes or as aid thereto a pressing device is provided, which operates

to turn the shoes forwardly into an inclined position and also serves to hold the shoes against rattling. In its preferred form this pressing device consists of a flat annular 5 spring H, which is arranged in the channel of the wheel-rim below the bearing-shoes. The bottom of the channel is constructed to form alternate depressions i and elevations i', the depressions being underneath the opposing 10 free ends of the shoes, while the elevations are radially in line or opposite the pivot-pins at the central parts of the shoes. The rear end of each shoe is preferably provided with an inward extension or lug j, which 15 bears against the spring between two elevations, and when free or unrestrained that portion of the spring by its resilience or relaxation normally moves the heavy rear end of the shoe outwardly, so that the outer bearing-surface of the same inclines forwardly. The movement of the shoes in this direction is limited by stops k, arranged underneath the front ends of the shoes and adapted to engage any suitable abutment, but preferably 20 against the adjacent outer side of the presser-spring H.

As the trolley-wheel rotates lengthwise of the conducting-wire its shoes are brought successively in engagement with the wire, each 30 shoe in its turn bearing flatwise throughout its entire length against the wire.

In order to cause the wire to be led smoothly and noiselessly from one shoe to another, the 35 shoes may be so constructed that they lap each other sidewise. The preferred way of doing this consists in forming a tapering tongue l on the rear end of each shoe and projecting the same rearwardly into a corresponding-shaped recess m in the front end of the next 40 following shoe, as shown in Figs. 1 and 2.

The construction and operation of the shoes are such that the bearing-surface of the same is practically parallel with the wire upon approaching and engaging the same, thereby 45 preventing the front corners of the shoes from engaging the wire and unduly wearing the same. One shoe at least is always in contact throughout its length with the wire, while at times two shoes bear fully against the same. 50 By this means a large surface contact between the trolley wheel and wire is at all times maintained and the free transmission of an ample amount of electric energy is permitted, thus avoiding sparking and loss of 55 power incident to the use of trolleys and other contact devices as heretofore constructed.

Although I have shown my improved electric contact device applied to a trolley-wheel, the same is obviously applicable to other devices requiring an electric current to be conducted from a movable part to a relatively 60 stationary part.

I claim as my invention—

1. An electric contact device comprising a 65 single rotary support, and an annular series

of contact-shoes pivoted directly on said support each provided with a tangential bearing-face, substantially as set forth.

2. An electric contact device comprising a single rotary support, an annular series of 70 contact-shoes each having a tangential bearing-face, and transverse pivot-pins passing directly through said shoes and support, substantially as set forth.

3. An electric contact device comprising a 75 single rotary support, an annular series of contact-shoes pivoted directly on said support and each having a tangential bearing-face, and a spring device operating to hold said shoes 80 yieldingly in position on said support, substantially as set forth.

4. An electric contact device comprising a single rotary support, an annular series of contact-shoes pivoted directly on said support and each having a tangential bearing-face, 85 and an annular spring mounted on said support and operating to hold said shoes yieldingly in position, substantially as set forth.

5. An electric contact device comprising a 90 rotary support, and an annular series of contact-shoes each of which is pivoted on said support and is heavier on one side of its pivot than the other so that the same will be turned by centrifugal force about its pivot upon rotating the support, substantially as set forth. 95

6. An electric contact device comprising a rotary support, an annular series of shoes pivoted on the support and a yielding presser device operating to turn said shoes constantly 100 in one direction, substantially as set forth.

7. An electric contact device comprising a 105 rotary support, an annular series of shoes pivoted on the support, and an annular spring arranged to bear against each shoe on one side of its pivot, substantially as set forth.

8. An electric contact device comprising a rotary support having its periphery constructed in the form of alternate elevations and depressions, an annular spring resting on said elevations, and an annular series of shoes pivoted on said support and engaging with said spring, substantially as set forth. 110

9. An electric contact device comprising a 115 rotary support having an annular channel in its periphery the bottom of said channel being constructed to form alternate elevations and depressions, an annular series of shoes arranged lengthwise in said channel and each pivoted opposite one of said elevations, and an annular spring resting on said elevations 120 and engaging with said shoes on one side of their pivots, substantially as set forth.

10. An electric contact device comprising a 125 rotary support having an annular channel, the bottom of said channel being constructed to form alternate elevations and depressions, an annular series of shoes arranged in said channel and each having a straight longitudinal bearing-face on its outer side, transverse pivot-pins each connecting one of said shoes between 130

its ends to said support above one of said elevations, and an annular spring resting on said elevations and engaging one end of each shoe and tending constantly to tilt the same so that 5 its bearing-face stands obliquely relatively to the periphery of said support, substantially as set forth.

11. An electric contact device comprising a single rotary support, and an annular series 10 of contact-shoes pivoted directly on said support and having their opposing ends overlapping one another but not connected, substantially as set forth.

12. An electric contact device comprising a 15 single rotary support, and an annular series of disconnected contact-shoes pivoted directly on said support and each having a tongue and

a recess at opposite ends, the several shoes being arranged so that the tongue of one enters the recess of another, substantially as set forth. 20

13. An electric contact device comprising a rim, two annular flanges arranged on opposite sides of the rim, one of said flanges being formed integrally with the rim while the other is detachably connected therewith, and an annular series of bearing-shoes pivoted between said flanges, substantially as set forth. 25

Witness my hand this 22d day of September, 1904.
